COMBINATION CRUSHER AND GRINDER

Vernie E. Clarke, Los Angeles, Calif., assignor to
 Christine Association, Inc., a corporation of California

Application May 27, 1940, Serial No. 337,485

1 Claim. (Cl. 83—53)

This invention relates to mills of the type commonly utilized for reducing the lump size of coal or ore and the like and has for an object the provision of a mill adapted to receive relatively large lumps of the material and reduce them to almost any desired degree of fineness in a single operation.

A more detailed object of my invention is to provide a mill of the general character indicated which operates upon the large lumps in a crushing action and upon the finer lumps in a grinding action, whereby the material is reduced in size not only to a much finer degree of fineness than can be obtained satisfactorily by any ordinary crushing action, but also to a uniformity of particle size sufficiently accurate and dependable to permit disposing with any screening of the product of the mill under many circumstances of its use.

Another object is the provision of a combined crusher and grinder of the character described, wherein both the crushing and grinding operations are performed by the same set of opposed operating jaws, which are so designed and so disposed with relation to each other that one part of the movable jaw moves in a line substantially perpendicular to the other jaw to develop the desired squeezing or crushing action upon the large lumps and another part of the movable jaw moves back and forth parallel to the surface of the other jaw in close contiguity thereto to develop the grinding action desired for comminution of the finer particles of the material.

Another object is so to arrange the jaws that the material being operated upon passes from the crushing to the grinding portion thereof and thence out of the mill continuously and by gravity and in such a manner that just so soon as a lump has been reduced in size the smaller particles to which it has been reduced will move on to another area of the mill where they again will be acted upon for further reduction and thereby assure that the mill is operating at full capacity and at maximum rate at all times.

Another object of my invention is to provide means for adjusting at least one of the jaws with respect to the other whereby to effect variation in the degree of fineness to which the material is reduced by the mill.

Another object is the provision of means for actuating the movable jaw in such a manner that an extremely high mechanical advantage is gained with the result that great crushing and grinding force can be exerted by the jaws without requiring an excessively powerful driving motor.

A still further object is the provision of a combined crushing and grinding mill of the general character indicated which in spite of its high efficiency and rapid rate of operation is of very simple construction and consequently inexpensive to manufacture, install and operate and which is so compact that it requires relatively little space for its installation.

The invention possesses other objects and advantageous features, some of which with those enumerated will be set forth in the following description of the preferred embodiment of my invention illustrated in the drawing accompanying and forming part of the specification. It is understood that I do not limit myself to the showing made by the said drawing and description as I may adopt variations of the preferred form within the scope of my invention as set forth in the claim.

20 Referring to the drawing:

Figure 1 is a top plan view of a combined crushing and grinding mill incorporating the principles of the present invention.

Figure 2 is a longitudinal vertical sectional view, the plane of the section being indicated by the line 2—2 of Figure 1 and the direction of view by the arrows.

Figure 3 is a view in side elevation of the operating end of the machine, showing the manner in which the movable jaw is mounted.

Figure 4 is a view similar to Figure 2, but of only the operating end of the machine and showing a slightly modified arrangement of the operating jaws.

35 Specifically describing the preferred embodiment of my combined crushing and grinding mill, the frame of the device comprises a pair of parallel longitudinal members 7 rigidly interconnected and retained in spaced relation by transverse members 8. All of these members can be formed conveniently of channel iron which facilitates their interconnection through the expedient of bolts 9 passing through the webs 11 of the longitudinal channels 7 and through the flanges 12 of the transverse channels 8.

40 A stationary crushing and grinding jaw 16 is mounted adjacent one end of the frame as by being secured to the inner face of the associated transverse frame member 8, a plurality of bolts 17 having countersunk heads 18 being employed for this purpose. Whereas the upper portion 19 of the jaw 16 is flat, its lower portion 21 is of an arcuate form and so arranged with respect to the flat portion 19 that the flat portion extends substantially tangentially from the arcuate portion,

The arc of the arcuate portion 21 is substantially 90 degrees and the flat portion is disposed substantially in a vertical plane.

The movable jaw 26 is carried by a transverse shaft 27 which extends across the frame and through aligned clearance holes 28 in the longitudinal member 1. Each end of the shaft 27 is supported in a bearing or journal 29 carried by a bracket 31 affixed to the outer face of the associated longitudinal frame member 7. Whereas any suitable bracket 31 may be employed, I have found it convenient to utilize a short length of angle iron wherein one flange 32 is welded as at 33 to the web 11 of the associated channel 7 with the other flange forming the bracket 31 by extending in a plane perpendicular to the face of the web 11. The base 34 of the bearing 29 is clamped against this bracket flange 31 as by a plurality of bolts 36; and by interposing one or more shims 37, between the base 34 and the bracket 31 adjustment of the shaft 27 may easily be arranged.

The movable jaw 26 is affixed to the shaft 27 between the spaced longitudinal frame members 7, for this purpose an anchoring plate 41 preferably being employed. This anchoring plate 41 is affixed rigidly and permanently as by welding to the shaft 27 in such arrangement that its forward face is substantially tangential with respect to the shaft. The movable jaw 26 is removably but rigidly affixed to the forward face of the anchoring plate 41 as by a plurality of bolts 42 preferably having countersunk heads 43 so as to leave the operating face of the jaw 26 substantially smooth. The jaw 26 is formed similarly to the stationary jaw 16 in that it comprises a flat portion 44 and an arcuate portion 46, the latter being arranged co-axially with respect to the shaft 27. Inasmuch as the shaft 27 is mounted in such position that its axis is closely adjacent or actually at the axis of the arcuate portion 21 of the stationary jaw 16, it follows that the two arcuate portions 21 and 46 are disposed substantially co-axially. Moreover, the shaft 27 is mounted in such a position that only a very narrow space or clearance 47 remains between the arcuate portions 21 and 46 as clearly shown in Fig. 2.

The flat portion 44 of the movable jaw 26 also extends tangentially from the arcuate portion 46 of that jaw; and the movable jaw 26 is so arranged that its tangential portion 44 slopes away from the tangential portion 19, thus providing a mouth 48 which tapers from its upper end toward the space 47 between the arcuate portions with the result that material 49 fed to the upper end of the tapering mouth 48 will assume a position therein, i. e., fall to a depth therein, determined by the lump size of that material, the larger lumps being retained adjacent the upper end of the tapering mouth 48, whereas the smaller lumps are permitted to fall further into the mouth with the result that all of the lumps regardless of their size will be wedged into firm engagement either with the actual crushing jaws or with other lumps. Hence when the jaws are caused to move towards each other the lumps will effectively be crushed, thus reduced in size to smaller particles whereupon they will fall by gravity further into the mouth 48 and closer to the space 47.

Means are provided for imparting the rocking motion to the shaft 27 and to the movable jaw 26 towards and away from the stationary jaw 16 about the axis of the shaft 27. For this purpose

a relatively long arm 51 is provided, preferably in the form of an I-beam, rigidly and preferably permanently secured as by welding 52 to the afterface of the anchoring plate 41 and to the shaft 27. From the shaft 27 the arm 51 extends longitudinally of the frame between the members 7 thereof and is provided upon its distal end with a plate 53 to which a bearing 54 is secured as by hold-down bolts 56. Journaled within this bearing is a pin 57 carried by the lower end of a pitman arm 58 having a bearing 59 upon its upper end, this bearing engaging an eccentric 61 carried by a shaft 62 journaled in aligned bearings 63 mounted upon the frame. One end 64 of the shaft 62 is extended to receive a gear 65 or the like whereby a prime mover of any suitable design may be operably coupled thereto to effect rotation of the shaft 62.

The type of reciprocating means described is 20 advantageous in that it affords an extremely high mechanical advantage. The eccentric 61 is offset from the axis of the shaft 62 a relatively small distance with the result that for each rotation of the shaft 62 only a slight longitudinal reciprocation of the pitman arm 58 results; and the arm 51 is of such length for each such reciprocation of the pitman arm 58 the movable jaw is 25 caused to move towards the stationary jaw 16 a considerably shorter distance but of course with greatly increased force. Accordingly very hard, 30 resistant materials can be comminuted by the device of the present invention without having to employ a very powerful prime mover.

Preferably a pair of opposed guiding plates 35 66 are provided at the ends of the jaws 16 and 26, a relatively close fit between the plates 66 and the ends of the movable jaw 26 being established so as to reduce to a minimum any leakage of material therebetween. These plates 40 preferably are removable so they can be replaced easily when worn.

As stated, the clearance 47 between the arcuate portions 21 and 46 is very slight with the 45 result that material is not permitted to flow from the machine until it has been reduced in size to a very fine state. This is a matter subject to adjustment for the reason that the plane of the brackets 31 upon which the bearings 34 are mounted, is preferably substantially perpendicular to the plane bisecting the arms described by the arcuate portions 21 and 36. Hence any variation in the thickness of the shim or shims 50 37 results in variation in the width of the clearance space 47 and corresponding variation in the 55 size of the particles to which the material 49 is comminuted. It is also important that the final comminution is performed in a grinding action 60 in contra-distinction to the crushing action which occurs within the tapered throat 48 for the reason that the only motion of which the 65 movable jaw 26 is capable is about the axis of the shaft 27. The tangential portion 44 of the movable jaw moves back and forth towards the tangential portion 19 of the fixed jaw 16 in a substantially straight line, whereas the arcuate portion 46 moves in its own arcuate plane about the axis of the shaft 27 and therefore does not alter its distance from the corresponding portion 21 of the fixed jaw 16. Therefore all particles 70 within the space 47 between these two arcuate portions are subjected not only to the tremendous pressure but also to a grinding action which results with the movement of the arcuate portion of one jaw substantially parallel to the opposed portion of the other jaw.

I have found the machine of the present invention to be exceedingly efficacious by so adjusting the shaft 27 that the clearance 47 between the arcuate portions of the jaws is just as slight as can be obtained without permitting actual frictional engagement between these parts. When so adjusted the machine is capable of comminuting material to a degree of fineness so extreme that it passes through a Tyler screen as fine as 200 mesh. Furthermore, this extremely fine degree of comminution is obtained directly from lumps of material 49 of the maximum size which the mouth 48 is capable of receiving; the flow of material through this tapering mouth being by gravity and continuous i. e., as soon as a lump is broken the smaller particles to which it has been reduced fall further into the tapering mouth where they are again acted upon because of the narrower width of this mouth 48 at that point, with the result that they are again reduced in size and thus permitted to advance by gravity further into the machine until they reach the area 47 between the arcuate portions where they no longer are crushed but are subjected to a grinding action where their final comminution is effected.

Attention is invited to the fact that in Fig. 2 the shaft 27 is so disposed that the area 47 wherein the grinding occurs is of gradually diminishing thickness for the reason that the axis of the shaft 27 is moved to the right slightly as viewed upon Fig. 2 from the axis of the arcuate portion 21 of the fixed jaw 16. Fig. 4 shows a slightly modified arrangement wherein the axis of the shaft 27 coincides with the axis of the arcuate portion 46' of the movable jaw 26' and also with the axis of the arcuate portion 21' of the stationary jaw 16'. Which arrangement

is advantageous depends of course upon the nature of the material being operated upon, the arrangement in Fig. 4 being resorted to where it is desired to extend the period during which the grinding of the material is carried out.

I claim:

In a combination crusher and grinder, a frame comprising a pair of spaced parallel longitudinal members having aligned openings therein, a transverse shaft extending with clearance through both of said openings, a plane surface bracket rigid with each of said frame members on the outer face thereof adjacent the associated opening, a bearing mounted on each of said brackets and supporting said shaft, adjusting means interposed between said bearings and brackets for shifting said shaft laterally thereof, a movable jaw mounted on said shaft between said longitudinal frame members and comprising an arcuate portion disposed substantially coaxially with said shaft and a portion extending tangentially from said arcuate portion, a fixed jaw mounted between said frame members and comprising an arcuate portion disposed adjacent and substantially concentrically with respect to said arcuate portion of said movable jaw and a portion extending tangentially therefrom, the tangential portions of said jaws being disposed in divergent relation to provide a mouth tapering to the space between said arcuate portions and means for rocking the shaft, the plane of the surface of each of said brackets on which the associated bearing is supported being substantially perpendicular to the plane bisecting said arcuate portion of said jaws, and said adjusting means being of uniform thickness plate.

VERNIE E. CLARKE.
